(57) **CLAIM**

The ornamental design for a motorcycle tire, as shown and described.

DESCRIPTION

FIG. 1 is a perspective view of an embodiment of a motorcycle tire;

FIG. 2 is a top elevation view thereof;

FIG. 3 is a bottom elevation view thereof;

FIG. 4 is a front elevation view thereof;

FIG. 5 is a back elevation view thereof;

FIG. 6 is a left side elevation view thereof;

FIG. 7 is a right side elevation view thereof; and,

FIG. 8 is an enlarged view of FIG. 4, showing a portion thereof.

The portions of the tire depicted in broken dashed lines of uneven length mark the boundaries of the claimed design. The portions of the tire depicted in long broken dashed lines of even length form no part of the claimed design. The short broken dashed lines of even length depict a border of an enlarged portion of the tire and form no part of the claimed design.
